ASH TRAY

Robert Harvey Galbreath, Denver, Colo.

Application November 14, 1949, Serial No. 6,034

Term of patent 14 years

(Cl. D85—2)

To all whom it may concern:

Be it known that I, Robert Harvey Galbreath, a citizen of the United States of America, residing at Denver, in the county of Denver and State of Colorado, have invented a new, original, and ornamental Design for Ash Trays, of which the following is a specification, reference being had to the accompanying drawing, forming part thereof.

In the drawing:

Fig. 1 is a plan view of an ash tray, showing my new design;

Fig. 2 is a side view thereof; and

Fig. 3 is a sectional view thereof, taken on the line 3—3 of Fig. 1; and

Fig. 4 is a sectional view thereof, taken on the line 4—4 of Fig. 1.

I claim:

The ornamental design for an ash tray, as shown.

ROBERT HARVEY GALBREATH.
